UNITED STATES PATENT OFFICE.

H. B. STEVENS, OF BUFFALO, NEW YORK, AND D. J. POWERS, OF MADISON, WISCONSIN, ASSIGNORS TO GEO. L. SQUIER, OF BUFFALO, NEW YORK.

IMPROVEMENT IN CANE-MILLS.

Specification forming part of Letters Patent No. 96,283, dated October 26, 1869.

To all whom it may concern:

Be it known that we, HENRY B. STEVENS, of Buffalo, in the county of Erie and State of New York, and D. J. POWERS, of Madison, in the county of Dane and State of Wisconsin, have invented Improvements in Sugar-Cane Mills; and we do hereby declare that the following is a full and exact description thereof, reference being had to the accompanying drawings, making part of this specification—

Figure 1 being a side elevation of a mill constructed with our improvements; Fig. 2, a top view thereof; Fig. 3, a horizontal section in a plane indicated by the line $x x$, Fig. 1.

Like letters designate corresponding parts in all the figures.

Our improvements are applied to vertical-roller cane-mills; and some of them consist in the adaptation to such mills of principles which have been secured to us in former Letters Patent by different arrangements to horizontal mills. These features are, first, wrought-iron strap-bolts around the bearing of the rollers; second, india-rubber springs or washers upon the strap-bolts to give elasticity to the main roller; third, the free removable scraper.

The application of these features of invention to vertical-roller cane-mills has been attended with much difficulty, so as to derive from them advantages corresponding with those secured by their use in horizontal-roller mills. Thus, while it is a matter of comparative ease to make the rollers of horizontal mills adjustable with vertical mills, owing to their peculiarities of construction and action, the successful adaptation of self-adjustment to the rollers has been regarded as a problem nearly impossible to practically perform. This difficulty will be appreciated when it is considered that the power is applied directly to the main roller, itself comparatively small, through a lever twelve or fourteen feet in length, and consequently a powerful leverage is exerted upon its bearings, thereby subjecting them to immense strain; and hence, though self-adjustment is all the more necessary or desirable, yet it is much more difficult to apply the principle without disarrangement. Unless the canes are fed with great care and regularity, the mills frequently clog, and are very liable to break, without elasticity and self-adjustability; and since, in order to pro-

duce the requisite pressure, the rollers have to be keyed up closely together in a rigid position, and all the strain, whether ordinary or excessive, from any special cause, has heretofore been resisted solely by the cast-iron frame or housing which held the rollers, such material has furnished inadequate strength to avoid breakage; or, if the rollers are adjusted too far apart, they will not crush the cane sufficiently nor fully express the juice. This defect is increased in the vertical mills by the additional difficulty in feeding the canes regularly in the vertical opening between the rollers, the canes having a tendency to settle downward in a mass at the lower ends of the rollers.

Our wrought-iron strap-bolts and india-rubber springs, as we apply them to the vertical mill, obviate all the difficulties above enumerated. We adjust the shaft or journals of the main roller A in boxes or bearings M M, which are movable horizontally in slots or openings in the top and bottom plates, D E, of the mill, the bearings being arc-shaped or in contact with no more than one-half of the surfaces of the journals, the opposite bearings being fixed, substantially as shown, and thereby limiting the movement of the journals in that direction, so as to allow a movement of the roller toward and from the inner rollers. Around these bearings the bend of the U-shaped wrought-iron strap-bolts H H fits substantially as shown, and extends thence straight across the top of the mill through tubular apertures d d formed in the plates D E, thence through and to a position beyond the fixed bearings of the minor rollers, where their projecting ends receive the india-rubber springs h h. The ends of the strap-bolts have screw-threads cut thereon to receive nuts, by which the degree of compression given to the springs is regulated. Metallic washers k k are inserted between the screw-nuts and springs. By thus screwing up the nut any degree of compression is produced, thereby rendering it wholly unnecessary to set and reset the rollers for different sizes of cane or variation in the quantity fed into the mill, because any increase of cane fed between the rollers separates them and increases the pressure in corresponding proportion. The strap-bolts take and sustain all the strain brought upon the rollers, whether from the pressure between the rollers or lat-

eral wrenching thereof by the driving lever or sweep, thereby avoiding breakage and obviating the necessity of care and nicety in feeding the canes to the rollers.

Our improved arrangement of the scraper or turn-plate P obviates the serious defects common to scrapers of vertical-roller mills in adjusting it to proper contact with the surface of the minor feed-roller, and in readily removing it from the mill when necessary, which necessity, with the usual construction of mills, occurs very frequently, at least every time it clogs. Ordinarily, the bolts and keys must be removed and the whole mill taken apart to remove the scraper, and with the best arrangements when the scraper is replaced the means of adjustment are wanting, or so defective as to render the scraper inoperative and nearly useless. All these difficulties we have overcome in the most complete manner, leaving nothing to be desired on the score of simplicity, convenience, and efficiency. The scraper P is of peculiar shape, the edge r being made to fit the face of the feed-roller B with a slightly concave face, in order to direct the cane through the space between the main roller A and delivery-roller C. It is held in place by and turns or is adjusted on an iron rod, p, which is inserted through the top plate, and simply fits in a semicircular groove in the back of the scraper, and thence extends down into or through the bottom plate. With this arrangement by simply withdrawing and replacing the rod p, the scraper can be removed and

reinserted almost in an instant, without disturbing any other parts of the machine, and without requiring a wrench or tool of any kind to effect the removal and insertion. The scraper turns freely around this rod as far as required, so that its edge may be properly adjusted to the periphery of the feed-roller by setting its handle t in the required position. The handle t of the scraper projects outward between the minor rollers and between the side housings, and it is provided with a setscrew, s, near its outer end, which bears against one of the housings, G, substantially as represented. Thus the handle serves both the purpose of a handle to move the scraper by and as a means of adjustment, by which any desired pressure can be brought to bear on the feed-roller.

We claim—

The turn-plate P, constructed substantially as described, and arranged with its semicircular groove, and rod p fitting therein, and the adjusting-screw s, in combination with the minor rollers of the vertical cane-mill, substantially as and for the purpose herein specified.

The above specification of our improvement in sugar-cane mills signed by us this 26th day of March, 1868.

H. B. STEVENS.
